A. A. HARTOGH

WALL POCKET

Filed Feb. 6, 1923

Inventor

Arthur A. Hartogh.
S. Stevens.

Attorney

UNITED STATES PATENT OFFICE.

ARTHUR A. HARTOGH, OF DULUTH, MINNESOTA, ASSIGNOR OF ONE-HALF TO JAMES W. BEAUDIN, OF DULUTH, MINNESOTA.

WALL POCKET.

Application filed February 6, 1923. Serial No. 617,201.

To all whom it may concern:

Be it known that I, ARTHUR A. HARTOGH, a citizen of the United States, residing at Duluth, in the county of St. Louis and State 5 of Minnesota, have invented certain new and useful Improvements in Wall Pockets, of which the following is a specification, reference being had therein to the accompanying drawing.

10 This invention relates to receptacles and refers particularly to a wall pocket or receptacle especially adapted for use in an automobile.

The principal object of the invention is 15 to provide a convenient receptacle for the storage of curtains, dunnage and the like in as compact and out of the way a manner as possible.

Another object is to provide such a form 20 of receptacle or pocket as convenient of access as possible and one in which the curtains of the automobile or similar thin flat objects may be easily placed and stored without wrinkling or other damage.

25 Still another object is to provide such a pocket which, if desired, may be quickly removed entirely from the automobile, and that without materially marring or otherwise defacing the car.

30 Other objects and advantages of the invention will appear in the further description thereof.

The figure in the accompanying drawing, forming part of this application, is a perspective view illustrating the application of 35 one of the receptacles as attached to the back of the front seat of an automobile.

Primarily the pocket comprises a flat centrally reinforced rectangularly shaped 40 fabric, the centermost portion 1 of which is reinforced by forming the fabric double and inserting therebetween stiffening material such as beaver board or the like, the same being wholly surrounded by suitable stitching 45 to retain it in place.

Beyond the reinforced portion the fabric may be double or single as desired and extended to about one-quarter the entire 50 length of the body portion forming flaps at either end thereof, the looped portion of which is indicated at 2 and the flap proper at 3, the latter being reinforced and formed in a similar manner to that of the body portion 1, the intermediate portions 2 acting

as a hinge as it were to the flaps, they being susceptible of adjustment in accordance with the thickness of the contents of the pocket.

On either longitudinal side of the body portion are formed narrow non-reinforced 60 strips 4 and 5, both of which adjacent their extreme edges are formed with halves of snap buttons of any well known construction such as "lift the dot" or the like. The flap 4 is on the bottom of the pocket and 65 designed to be buttoned either into a row of buttons previously placed therefor in the bottom 6 of the car or along the lower edge of the back of the front seat, which is indicated at 7; while the other flap 5 I 70 prefer to stitch longitudinally its center as indicated at 8 to reinforce it somewhat, the same being preferably stitched while in a slightly bent position so as to form a convenient shape for buttoning up against the 75 back of the seat 7 adjacent the upper edge thereof to a row of buttons indicated at 9 previously placed therefor.

The pocket may be made of any fabric desired and reinforced to suit circumstances, 80 and it is readily seen that when dropped down onto the bottom of the car the flaps 3-3 may be thrown open and the curtains of the car neatly folded therebetween, and when the flaps are put back onto the curtains, or whatever the contents of the pocket may be, the same may be raised up bodily and buttoned into position, as shown in dotted lines, against the back of the front seat 7; thus an exceedingly convenient, neat 85 and efficient receptacle for the purpose intended results.

If desired the lower edge flap 4 may be reinforced with a metal or wooden strip and attached only at its ends, or in fact this 95 flap may be permanently fixed to the bottom of the car or lower edge of the seat back without departing from the spirit of the invention.

Having thus described my invention, 100 what I claim as new and desire to secure by Letters Patent, is:

1. The combination with an upright wall, of a pocket therefor comprising a major body portion of thin suitable material having inwardly foldable ends for engaging the contents of the pocket, and means for holding the longitudinal edges of the pocket 105

either permanently or removably against the upright wall.

2. The combination with a back upright wall of a vehicle seat of a pocket comprising a major body portion of thin suitable material having inwardly foldable ends for engaging the contents of the pocket, and means for holding the longitudinal edges

of the pocket either permanently or removably against the upright wall.

In testimony whereof I hereunto affix my signature in the presence of two witnesses.

ARTHUR A. HARTOGH.

Witnesses:

S. GEO. STEVENS,

S. C. BRONSON.
